UNITED STATES PATENT OFFICE.

TITO LIVIO CARBONE, OF CHARLOTTENBURG, GERMANY, ASSIGNOR TO GENERAL ELECTRIC COMPANY, A CORPORATION OF NEW YORK.

INCLOSED FLAMING-ARC LAMP.

1,154,093.

Specification of Letters Patent. Patented Sept. 21, 1915.

Application filed July 28, 1911. Serial No. 641,145.

To all whom it may concern:

Be it known that I, TITO LIVIO CARBONE, a citizen of the Empire of Germany, and a resident of Charlottenburg, Germany, have invented certain new and useful Improvements in Inclosed Flaming-Arc Lamps, of which the following is a specification.

This invention relates to inclosed flaming arc-lamps, and more particularly, to those which are known as long burning lamps in which the electrodes are impregnated with salts, which give luminosity to the arc.

In lamps of this character, as exemplified by my Patent No. 975,935, a circulation of the inclosed air together with the products of combustion takes place, these products rising into a condensing chamber where the solid matter contained in them is largely deposited, and then returning to the arc inclosing globe, still carrying with them some solid matter which is deposited in the globe, but remote from the portion thereof which is designed to emit light. The air which is primarily in the arc inclosure and that which afterward is sparingly admitted, contains, of necessity, water vapor, and this has proved to be a source of great inconvenience in that it combines with some of the products of combustion and forms an etching medium whereby the inner wall of the globe is being etched and its transparency or translucency is permanently impaired; also the deposition of the moisture upon the globe promotes the adherence of the solid products of combustion thereto; it also causes deposition of products of combustion on such parts of the globe where it would not otherwise occur.

With the view of overcoming these defects, it is the object of my invention to make and keep the air in the arc inclosure dry, and I accomplish this by placing a moisture absorbing material in the arc inclosure at such place where the circulating gases have to pass and where it does not impede the emission of light.

In the accompanying drawing I have illustrated one embodiment of my invention as follows:—

Figure 1 is a side elevation, partly in section, of the lamp equipped with my improvement; Fig. 2 is a plan view of the container for the absorbing material on a reduced scale, and Fig. 3 is an elevation of a

portion of the container viewed at right angles of the section plan 3—3, Fig. 2.

The arc inclosure is composed of the glass globe 11 and the condensing chamber 12, and it will be understood that the mineralized electrodes are suitably mounted and regulated as is customary in such lamps. The glass globe is held against the condensing chamber by bails as usual and air is only sparingly admitted to the arc inclosure at the places where the upper electrode 65 passes into the inclosure and where the holder of the lower electrode (not here shown), descends into the globe; some little air may also leak in where the upper edge of the globe is seated against the condensing 70 chamber. All these matters are well known and need not be described in detail.

Within the condensing chamber, in the bottom thereof, near or at the periphery, the absorbing material is placed, preferably held in a hose-shaped wire netting or screen 13. The absorbing material used is by preference magnesium, or what is commercially known as carbonate of magnesia, in blocks 14, of a size that can be easily filled into the 80 wire hose and will still allow that hose to be bent into ring form and sprung into place in the condensing chamber, as shown in the drawing. The location of the absorbing material in the bottom of the condensing 85 chamber is such that the circulating gases carrying moisture will pass in contact with that material, so that it will act to greatest advantage as a moisture absorber. The meshes of the wire screen hose are so wide 90 that the circulation of the gases through them is not appreciably impeded. The wire gauze container of the absorbing material is a convenient means for inserting and for removing for renewal the absorbing material.

I have found that the use of the absorbing material in the location indicated is quite effective to keep the air in the arc inclosure practically free of moisture, so that 100 no etching fluids are formed and the other inconveniences hereinbefore indicated are avoided.

Having thus described my invention, I claim as new and desire to secure by Letters Patent:—

In an inclosed flaming arc lamp provided with a condensing chamber for the

deposition therein of the products of combustion, a hose of wire gauze within the condensing chamber in the path of the circulating gases, containing blocks of moisture absorbing material, substantially as described.

5 In testimony, that I claim the foregoing as

my invention, I have signed my name in presence of two subscribing witnesses.

TITO LIVIO CARBONE.
